(57) **CLAIM**

The ornamental design for a display screen with graphical user interface, as shown and described.

DESCRIPTION

The FIGURE is a front view of a display screen with graphical user interface showing our new design.

The dash-dot outer broken line perimeter showing the display screen and all other broken lines within showing text and elements of the graphical user interface are for the purpose of illustrating portions of the article and form no part of the claimed design. Portions of the graphical user interface that have shading indicate a contrast of appearance.
